UNITED STATES PATENT OFFICE.

ELMER HASLETT, OF SAUSALITO, CALIFORNIA.

DESIGN FOR A JAR OR SIMILAR CONTAINER.

Application filed April 29, 1927. Serial No. 21,792. Term of patent 14 years.

To all whom it may concern:

Be it known that I, ELMER HASLETT, a citizen of the United States, residing at Sausalito, in the county of Marin and State of California, have invented a new, original, and ornamental Design for Jars or Similar Containers, of which the following is a specification, reference being had to the accompanying drawing, forming a part thereof.

In the drawing:

Fig. 1 is an elevation of a jar or similar container showing my new invention, and

Fig. 2 is a perspective of the same.

The design includes a jar or similar container having approximately the configuration shown, with the surface of the top and of a peripheral band at the bottom having a color effect different from that of the peripheral surface between said band and top.

I claim:

The ornamental design for a jar or similar container, substantially as shown and described.

ELMER HASLETT.
